DESIGN FOR A REAR FRAME BODY FOR A VELOCIPED

Bert J. Anderson, Hammond, Ind.

Application October 11, 1934, Serial No. 53,582

Term of patent 14 years

To all whom it may concern:

Be it known that I, Bert J. Anderson, a citizen of the United States, residing at Hammond, in the county of Lake and State of Indiana, have invented a new, original, and ornamental Design for a Rear Frame Body for a Velocipede, of which the following is a specification, reference being had to the accompanying drawing, forming part thereof.

Figure 1 is a rear elevation of a rear frame

body for a velocipede, showing my new design.

Figure 2 is a side elevation thereof and shows the curvature of the cylindrical upper portion.

Figure 3 is a slightly reduced perspective view taken from the rear.

I claim:

The ornamental design for a rear frame body for a velocipede as shown and described.

BERT J. ANDERSON.
